NELLIE KITTS HICKS, OF MAYWOOD, CALIFORNIA

INSTRUCTION CHART

Application filed September 3, 1930. Serial No. 479,495.

My invention relates to an instruction chart that is especially designed for use in the instruction of pupils in schools and the like and the principal object of my invention is, to provide a relatively simple, practical and inexpensive chart that is constructed and marked with data so that it may be conveniently and advantageously used for the teaching of multiplication and division.

A further object of my invention is, to provide an instruction chart of the character referred to that includes a suitable support and housing and a pair of flexible charts that are mounted for operation on spring actuated rollers of the type that are generally used for the support of window shades and which charts may be easily and quickly manipulated so as to present problems in multiplication and division and the results thereof, thereby providing a simple, convenient and accurate instruction chart.

With the foregoing and other objects in view, my invention consists in certain novel features of construction and arrangement of parts that will hereinafter be more fully described and claimed and illustrated in the accompanying drawings in which:

Fig. 1 is a front elevational view of my improved instruction chart and showing the parts thereof adjusted so as to present the results of multiplication of the digit 9.

Fig. 2 is an enlarged vertical section taken on the line 2—2 of Fig. 1.

Fig. 3 is a rear elevational view of the lower end portion of the flexible chart that carries the products resulting from multiplication of the digits.

Figs. 4, 5 and 6 are front elevational views of the chart with the parts thereof shifted into different positions so as to present different problems in multiplication and division.

The combined support and housing for my improved chart may be formed of wood or metal and such support and housing comprises a rear wall or panel 10, a horizontally disposed upper panel 11 and end walls 12, said parts being arranged so as to form an elongated housing open at front and at the

bottom. If desired the housing may be provided with a suitable cover which is applied to said housing when the same is in storage or during transportation.

Secured to the upper portion of the rear panel 10 and projecting upwardly therefrom are perforated ears 13 that are adapted to receive pins, screws or the like so as to support the housing on a wall or other fixed member.

Secured to the front face of rear panel 10 adjacent to the end walls 12 and midway between the top panel 11 and the lower edges of the rear panel 10 and end walls 12 are brackets 14 that serve as bearings for the pintles on the ends of an ordinary spring-actuated roller 15 such as is used for the support of window shades.

Secured to and projecting forwardly from the rear panel 10 just below the brackets 14, are similar brackets 16 that serve as bearings for the pintles of a spring actuated roller 17 and which latter occupies a position parallel with and just below the roller 15.

Projecting forwardly from the upper portion of panel 10 are brackets 18 that serve as bearings for the journals of a roller 19 and which latter occupies a position parallel with and above roller 15. There are no springs associated with roller 19 so that the same rotates freely in both directions.

Secured to roller 15 in any suitable manner is one end of a flexible sheet 20 of paper, fabric or a combination of paper and fabric and the front face of which sheet bears a row of digits and lines as hereinafter more specifically described and thus said flexible sheet forms a chart that cooperates with another chart in producing the desired results.

Secured to the lower free end of the flexible sheet 20 is a small reinforcing rod or strip 21. When properly positioned for use, the flexible member 20 depends from the rear portion of the roller 15.

Formed in sheet 20 at a point midway between the side edges thereof and a short distance above the lower free end of said strip is an opening 22, preferably circular in form and appearing on the front face of said member 20 a short distance above and

- parallel with the reenforcing member 21 is a horizontally disposed row of equal sized areas 23, preferably square, and which are bounded by straight lines 24.
- 5 Appear on the surface of member 20 within these areas 23 are the nine digits and also the numbers 10, 11 and 12. If desired spaces or areas 23 may be provided for the accommodation of numbers higher than 12.

- 10 The digits and numbers just mentioned may be arranged so that they do not appear in consecutive order, such arrangement being illustrated in Fig. 1 or, if desired, they may be arranged so that they may be read in proper numerical order from left to right.
- 15 These digits and numbers from 1 to 12 inclusive constitute the multipliers when my improved chart is utilized for teaching multiplication.

- 20 Appear on the face of member 20 and extending from the upper central portions of the areas in which the areas 23 in which the digits and numbers appear upwardly and inwardly, are straight converging lines 25 which terminate at the lower portion of the opening 22. Appear on the face of flexible member 20 and extending from the points where the lines 25 join the lines at the upper edges of the areas 23, upwardly or longitudinally of said member 20 are lines 26 that are parallel with each other and parallel with the side edges of member 20. These lines 26 are formed or colored so that they may be readily distinguished from the inclined lines 25. If desired the lines 26 may be solid or continuous or they may be dotted or dash and dot.

Secured in the conventional manner to spring actuated roller 17 is one end of a flexible sheet 27 of suitable material such as paper, fabric or a combination of paper and fabric and from said roller 17 the web of this sheet extends upwardly in front of roller 15, thence over free running roller 19 and thence downwardly behind flexible sheet 20.

This flexible member 27 is somewhat longer than flexible member 20 and the lower free end of said member 27 may be provided with a small reenforcing rod or strip 28.

Appearing on the front face of flexible member 27 midway between the side edges thereof is a vertically disposed row of digits from 2 to 12 inclusive, the same being spaced equi-distant from each other and arranged so that they will appear in succession through the opening 22 in the flexible member 20 as the latter is raised or lowered or as member 27 is raised or lowered relative to member 20. This vertical row of digits function as multiplicands when the chart is utilized for teaching multiplication.

Appearing on the rear face of the flexible member 27, within areas or spaces 29 are

rows which will be products when the chart is utilized for teaching multiplication and these numbers are arranged in horizontal parallel rows and when the chart is properly arranged for use the numbers appear 70 upside down on that portion of the flexible member that hangs below roller 19, but when said rows of numbers are brought into view on the front surface of that portion of member 27 between the rollers 19 and 17 they 75 appear in proper readable positions and they are spaced laterally so as to occupy positions in vertical alignment with the corresponding multiplier numbers within the spaces 23.

The numbers appearing in the transversely disposed rows on the rear face of member 27 are the products of the multiplicands and the multipliers.

Inasmuch as the lateral spacing of the 85 areas 29 containing the products, corresponds with the lateral spacing of the areas 23, the vertically disposed parallel lines 26 that extend upwardly from the spaces 23, coincide with or lead directly to the lower 90 portions of the spaces 29 that are occupied by the product numbers.

In the operation of my improved chart for the teaching of multiplication flexible member 20 is drawn downward until the 95 opening 22 occupies a position a short distance below roller 17 and flexible member 27 is now drawn downward and adjusted after the manner of the ordinary spring shade roller so that the desired multiplicand 100 appears through opening 22.

Inasmuch as the rows of product numbers on the rear face of member 27 are properly arranged relative to the digits functioning as multiplicands, the row of numbers that are the products of multiplication of the multiplicand appearing through opening 22 by the multipliers in the spaces 23 will appear on the front face of that portion of member 27 that is positioned between the 110 rollers 19 and 17. For example, when the chart is positioned as illustrated in Fig. 1, a pupil noting the multiplicand 9 and then following the diagonal lines 25 that lead downwardly from the opening 22 through 115 which the multiplicand appears, to the multipliers in the spaces 23 and then following the distinctively marked or colored lines 26 upwardly to the exposed portion of the face 120 of flexible member 27 may observe the products of multiplication of the multiplicand.

Any adjustment or change of position of member 27 to bring one of the multiplicands into view through opening 22 automatically effects a change in the row of products brought into view on exposed portion of the face of flexible member 27 and thus the teaching of multiplication may be very readily accomplished.

The length of flexible member 27 is such 130

that there is a blank space beyond the rows of products.

Various adjustments and manipulations of the flexible members 20 and 27 may be made in order to bring about different problems in the teaching of multiplication and division and as a result the teaching and rating of pupils in accuracy, speed and progress may be readily and conveniently accomplished.

In Figs. 4, 5 and 6, I have shown the flexible members adjusted to different relative positions in order to produce different problems used in teaching multiplication and division.

Thus it will be seen that I have provided an instruction chart that is relatively simple in construction, inexpensive of manufacture, capable of being quickly and easily adjusted to present different problems and which chart is very effective in performing the functions for which it is intended.

It will be understood that minor changes in the size, form and construction of the various parts of my improved instruction chart may be made and substituted for those herein shown and described without departing from the spirit of my invention, the scope of which is set forth in the appended claims.

I claim as my invention:

1. An instruction chart, comprising a support, a pair of spring actuated rollers journaled on said support and disposed in parallel arrangement one directly above the other, a free running roller journaled on said support above and parallel with said spring actuated rollers, a flexible member secured to the upper one of said spring actuated rollers and depending from the rear thereof, said flexible member being provided at a point midway between its sides with an opening and with a transversely disposed row of digits and numbers that are arranged parallel with and adjacent to its lower edge, a flexible member secured to the lower one of the spring actuated rollers and extending upwardly in front of the upper one of the spring actuated rollers, over the free running roller, thence downwardly behind the spring actuated rollers and the depending portion of the flexible member that is carried by the upper one of said spring actuated rollers, the front face of the second mentioned flexible member bearing a centrally arranged vertically disposed row of digits and numbers that are visible in succession through the opening in the first mentioned flexible member as one flexible member is adjusted vertically relative to the other and the rear face of the second mentioned flexible member bearing transversely disposed rows of digits and numbers that bear relation to the digits and numbers on the front faces of the flexible members and which appear in succession on the front face of that

portion of said second mentioned flexible member that is positioned between the free running roller and the lower one of the spring actuated rollers.

2. An instruction chart, as set forth in claim 1, and the front face of the first mentioned chart bearing straight lines that lead from the lower portion of the opening in said flexible member to the digits and numbers forming the transversely disposed row that is arranged parallel with and adjacent to the lower edge of said flexible member.

3. An instruction chart, as set forth in claim 1, with the front face of the first mentioned chart bearing straight lines that lead from the lower portion of the opening in said flexible member to the digits and numbers forming the transversely disposed row that is arranged parallel with and adjacent to the lower edge of said flexible member and the front face of said first mentioned flexible member bearing distinctive parallel lines that extend upwardly from the areas that are occupied by the digits and numbers appearing on the lower portion of said flexible member.

In testimony whereof I affix my signature.
